[57] CLAIM

I claim the ornamental design for a solar powered lighting fixture, as shown and described.

DESCRIPTION

FIG. 1 is a perspective view of the solar powered lighting fixture, embodying my new design, it being understood that the support bracket and lamps shown is phantom outline in this and other Figures are optional members, not forming part of the design;

FIG. 2 is a front, elevational view of the lighting fixture in FIG. 1, it being understood that the rear elevational view is identical;

FIG. 3 is a right side elevational view of the fixture of FIG. 1;

FIG. 4 is a left side elevational view of the fixture of FIG. 1;

FIG. 5 is a top, plan view of the fixture of FIG. 1;

FIG. 6 is a bottom, plan view of the fixture of FIG. 1;

FIG. 7 is a perspective view of another embodiment of solar powered lighting fixture;

FIG. 8 is a front, elevational view of the lighting fixture of FIG. 7, it being understood that the rear elevational view is identical;

FIG. 9 is a right side elevational view of the fixture of FIG. 7;

FIG. 10 is a left side elevational view of the fixture of FIG. 7;

FIG. 11 is a top, plan view of the fixture of FIG. 7; and,
FIG. 12 is a bottom, plan view of the fixture of FIG. 7.
